UNITED STATES PATENT OFFICE.

CONRAD GENJACK, OF VANCOUVER, BRITISH COLUMBIA, CANADA.

CAN-OPENING DEVICE.

Application filed April 25, 1927. Serial No. 186,391.

My invention relates to improvements in can opening devices which are particularly adapted for use in removing "pressed on" covers from cans, and which are preferably secured to the covers by the manufacturer and sold with the cans. The objects of the invention are to provide means whereby a leverage may be applied between the rim of the cover and the can top to raise the cover that it may be removed without difficulty or without having recourse to the use of other tools or devices.

The invention consists essentially of a lever preferably hingingly connected upon the rim of the can cover and adapted to have its bearing point brought into contact with the can top, as will be more fully described in the following specification, in which:

Fig. 1 is a fragmentary sectional view 20 of a can and its cover in closed position showing the can opener attached thereto.

Fig. 2 is a sectional view showing the cover partly raised.

Fig. 3 is a plan view of the invention.

Fig. 4 is a view showing the bearing point of the can opener.

Fig. 5 is a view showing a modified method of forming the can cover and the top wall of the can to permit the can opener to lie 30 below the upper horizontal plane of the can.

In the drawings like characters of reference indicate corresponding parts in each figure.

The numeral 1 indicates a can having side 35 walls 2 and an apertured top wall 3 which usually consists of an annular margin into which a cover, generally indicated by the numeral 4 is tightly pressed. The can cover 4 is provided with a peripheral rim 5 40 mounted by an outwardly turned flange 6 which is adapted to extend over the margin or top wall 3 of the can in the usual way.

The numeral 7 indicates generally the can opener which is preferably formed 45 from a piece of sheet metal and provided at its inner end with a lever arm 8 having downwardly bent sides 9 which are adapted to lie in close contact with the cover when in normal position and provide convenient 50 access for the point of the user's finger at the extreme inner end 10 of the lever. The outer end of the opener 7 is downwardly turned to form a tongue or point of bearing 11, which is preferably provided with an 55 inclined face 12, the purpose of which will hereinafter appear. Intermediate the length

of the opener 7 a pair of side extensions 13 are provided which are bent into substantially tubular form about the flange 6 of the can cover 4 to form a hinge bearing about 60 which the opener is rocked.

In the modification shown in figure 5 a portion of the top wall 3 is depressed as at 14, shown in dotted line, and the peripheral rim 5 of the cover 4 is similarly depressed as at 15, the ends of such depressions being gradually sloped as at 16 so as to permit the can opener 7 to be moved circumferentially from its normal position within the recess 15. The recess 15 is of such a 70 depth as to allow the top surface of the opener 7 to lie below the top of the side walls 2 of the can, so that the top of one can will provide a level base for another which is superimposed upon it in packing 75 or storage.

In use, the inner extremity 10 of the can opener will be raised by the finger or thumb, which will cause the tongue 11 to bear upon the top margin 3 and raise the side of the 80 cover 4 in which the opener 7 is positioned. Should one movement of the opener be insufficient to free the cover from the can, the opener is subsequently moved in a clockwise direction about the rim 5 to a new position when a further lifting effort would be applied.

It is sometimes found that the material used in the production of the top margin 3 of the can is very light so that the pressure 90 of the tongue 11 produces an indentation therein, where this occurs the depression of the inner end 10 of the opener will so elevate the upper end of the inclined extremity 12 of the tongue 11 as to enable the opener to be moved circumferentially in a clockwise direction, that a new point of contact with the margin may be found in order that further lifting of the cover can be effected.

What I claim as my invention is:

A can opener for cans provided with press on covers having a peripheral rim, comprising a lever adapted to be hingingly applied to the rim of the cover and having a downwardly turned tongue adapted to bear upon the can as the lever is raised to lift the cover from the can, said tongue having an inclined lower extremity.

Dated at Vancouver, B. C., this 16th day of April, 1927.

CONRAD GENJACK.
